UNITED STATES PATENT OFFICE.

JENNIE WALLIN, OF ROCKFORD, ILLINOIS.

ACROBAT'S STAND.

1,128,201.

Specification of Letters Patent.

Patented Feb. 9, 1915.

Application filed May 4, 1914. Serial No. 836,247.

To all whom it may concern:

Be it known that I, JENNIE WALLIN, a citizen of the United States, residing at Rockford, in the county of Winnebago and 5 State of Illinois, have invented a new and useful Acrobat's Stand, of which the following is a specification.

This invention relates to a novel stand for acrobats and more particularly to a 10 stand which is used in connection with a slack wire performance.

One object of the present invention is to provide a stand adapted to support an acrobat in different positions while holding one 15 end of a slack wire in the mouth.

A further object is to provide a stand of ladder-like characteristics and upon which is mounted a platform with suitable foot holds thereon and upon which platform are 20 mounted suitable supporting means so that the acrobat may, while holding one end of a slack wire in the mouth, assume various positions such as standing, sitting, bending backward, etc.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

35 In the accompanying drawings—Figure 1 is a perspective view taken from above the stand. Figs. 2 and 3 are perspective views taken from below showing two methods of using the same.

Referring to the drawing by characters of reference, 1—1 designate standards, between which extend a plurality of cross struts 2 which act in the capacity of ladder rungs with the standards 1 as the stiles. The lower ends of the standards are bent or flared outwardly as at 3 so as to increase the stability of the entire structure by increasing the distance between the points 45 of support thereof. A platform 4 is rigidly secured to the standards 1 and is made rigid thereto by the angularly disposed braces 5. The platform is of sufficient dimensions to accommodate a person thereon 50 and is accessible by climbing the ladder-

like structure formed by the standards 1 and cross struts 2. Suitable toe holds 6 are secured upon the platform adjacent the outer edge and afford gripping means for the acrobat during the use of the stand, as 60 will be more fully hereinafter pointed out.

Positioned a distance above the platform and extending parallel therewith are the horizontal bars 7 rigidly secured at their forward extremities to the standards 1 and 65 provided at their rear extremities with the toe holding members 8. A bar or back rest 9 serves as a support for the back of the acrobat when the feet are disposed in the foot holding members 8. The standards 70 project a distance above the back rest 9 and form what are termed the handles 10, providing a suitable grip for the acrobat's hands when standing upon the platform and facing toward the opposite stand. 75 Suitable guy wires 11 are provided and are secured to the standards 1 and lock the stand rigidly in an upright position. The stand as thus constructed is used by an acrobat who holds one end of a slack wire 80 in the teeth while a second acrobat performs on said wire. The acrobat upon the stand may assume a position with the feet in the toe holds 8, with the back rest 9 supporting the small of the back and with the 85 hands free, the acrobat being prevented from being pulled off of the stand by reason of the legs contacting with the handles 10. It is to be noted in this connection that the acrobat's head is below the slack wire 90 and that the stress is applied to the body of the acrobat in a downward direction and which weight will be effectively distributed to the back rest 9, the handles 10, and the toe holds 8, thus preventing undue pressure 95 being brought to bear upon a single point or place of the acrobat's body. A somewhat similar posture may be maintained by the acrobat with the feet in the lower toe holds 6 with the body bent backward 100 and with the arms grasping the standards 1 a slight distance above the horizontal bars 7 in such manner that the upper portions of the acrobat's arms adjacent the shoulders rest upon the said horizontal bar. 105 This takes up the downward stress while the hands and toes effectively take up the horizontal pull. In like manner, the acrobat may assume a number of different postures in which the weight or force exerted 110

upon the acrobat will be distributed so that excessive pressure at one point of contact will be avoided.

Having thus fully described my invention, what I claim is:—

- 5 1. An apparatus of the class described comprising upright standards, a platform supported thereby, toe holding members carried by said platform, horizontal bars 10 positioned above said platform and rigidly secured to said standards projecting rearwardly therefrom.
- 15 2. An apparatus of the class described, comprising upright standards, a platform supported thereby, toe holding members carried by said platform, horizontal bars positioned above said platform and rigidly secured to said standards, projecting rearwardly therefrom, and means engaging said 20 standards adapted to hold the same in an upright manner.
- 25 3. An apparatus of the class described, comprising upright standards, a platform supported thereby, toe holding members carried by said platform, horizontal bars positioned above said platform and rigidly secured to said standards, projecting rearwardly therefrom, means engaging said standards adapted to hold the same in an 30 upright manner, and cross struts extending between and secured to the said standards for bracing the same and forming a ladder-like structure therewith, rendering accessible the said platform.
- 35 4. An apparatus of the class described, comprising upright standards, horizontal bars projecting therefrom and secured thereto, toe holding members carried at the extremities of said horizontal bars, and a back rest extending between said standards 40 above said horizontal bars and positioned a distance below the extremities of the standards, said standards above the back rest forming gripping handles.
- 45 5. An apparatus of the class described, comprising a pair of upright standards, the lower extremities thereof bent in opposite directions and forming flaring supporting legs, a plurality of cross struts extending between said standards, bracing the 50 same, and forming a ladder-like structure therewith, a platform carried by and projecting rearwardly from said standards, rendered accessible by said ladder-like structure, a pair of horizontally extending 55 bars secured to the said standards, positioned above the said platform, and provided with toe holding members at the outermost extremities thereof, and a back rest extending between the said standards 60 and positioned above the said horizontally extending bars and below the upper extremities of the said standards, the portions of the standards projecting above the back rest forming gripping handles.

In testimony that I claim the foregoing as my own, I have hereto affixed my signature in the presence of two witnesses.

JENNIE WALLIN.
